[57] CLAIM

The ornamental design for a combined housing for doorbell switch, signal system and message cabinet, substantially as shown and described.

DESCRIPTION

FIG. 1 is a top front perspective view of a combined housing for doorbell switch, signal system and message cabinet showing my new design, with the cover in an open position;

FIG. 2 is a top front perspective thereof with the cover in the closed position;

FIG. 3 is a front elevational view thereof;

FIG. 4 is a top plan view thereof;

FIG. 5 is a right side elevational view, the left side, but for lights and button switch, being a mirror image thereof;

FIG. 6 is an end elevational view of a writing pen;

FIG. 7 is a bottom plan view of the pen shown along the line 8—8 of FIG. 7;

FIG. 8 is a side elevational view of the pen thereof; and FIG. 9 is a rear elevational view thereof.

The pen is shown separately in FIGS. 7, 8 and 9 for clarity of illustration only and the line cord is shown fragmentarily for ease of illustration.
